PROCESS FOR GASIFYING FUELS

Roman Rummel, Brühl, Köln, Germany

Application May 23, 1956, Serial No. 586,759

Claims priority, application Germany May 25, 1955

1 Claim. (Cl. 48—197)

The present invention relates to an improved and efficient process for the gasification of fuels and to an apparatus for carrying out this process.

It is known to gasify finely divided, solid or liquid fuels by introducing fuels and gasifying agents tangentially to the wall of the body of a gas producer or to an imaginary circle of small diameter in such a manner that the reactants in the body are caused to rotate about the axis of the body, and withdrawing the resultant slag in molten condition.

In these prior art processes, fuel is gasified at high temperature in a whirlpool of slag or in a cyclone-type fluidized bed of dust particles. The fuel is not gasified completely in this process so that part of the sensible heat of the unfinished gas is utilized for the gasification reaction. Thus, an after reaction of the gas with the residual fuel carried along therewith takes place on the path of the reactants through the body. It has been shown that, by the helical motion of the gas column in the body, the fuel particles suspended in the gas are thrown onto the wall where the gas is reduced. However, the gas no longer reacts in the core of the gas column, since the core is substantially free of fuel. So the gas leaves the body of the gas producer with a high proportion of carbon dioxide and a low calorific value. Attempts have been made to lengthen the reaction path by modifying the equipment, e.g. by arranging tall bodies, but the problem can be solved only partially in this manner, since complete reduction of the gas cannot be accomplished although, by friction, the helical motion of the gas column is gradually slowed down on the long path through the body and part of the gas from the interior of the body undergoes further reaction. In addition, the cooling of the gas to lower temperatures as a result of the tall body is detrimental to the after reaction of the gas. The sensible heat dissipated through the wall of the body is withdrawn from the reduction process.

In accordance with the present invention, it has been found that the disadvantages associated with the aforesaid prior art processes for the gasification of fuels in a body of a gas producer into which fuels and gasifying agents are introduced separately or jointly in such a manner that the fuels, gasifying agents and their reaction products rotate about the axis of the body, can be avoided by deflecting the helical path of the produced unfinished gases and the non-gasified residual fuel particles rotating about the axis of the body of the gas producer during the gasification reaction, into a direction substantially parallel to the axis of the body, and distributing the fuel particles carried along with the gas all over the sectional area of the body. Thus, the reaction of fuels and gasifying agents takes place according to the invention not only within a narrow zone on the wall of the body, but all over the sectional area on a short path through the body. By deflecting the helical gas stream into a direction parallel to the axis of the body, the fuel particles are prevented from being thrown onto the wall of the body. This ensures a complete reaction between gas and fuel.

2

The gas produced shows an optimum calorific value. The reaction space is fully utilized, so that the provision of very high equipment is not required. By concentrating the reaction process to a very small volume the loss of heat is slight and an optimum quantity of heat is supplied to the gasification process, whereby the calorific value of the gas produced is further increased.

The deflection of the initially helical path into a parallel turbulent stream can be accomplished according to 5 the invention for instance by arranging appropriate deflecting and orienting means in the body of a gas producer. These deflecting and orienting means may be constructed in various manners, which will be more fully explained below by way of examples. It is of advantage to provide deflecting and orienting means which are adapted to secure a temporary increase of the flow velocity and, consequently, an increase of the relative velocity between the gas and fuel.

By reason of the low activity of the fuel particles 10 which are substantially larger than the gas molecules, the relative velocity between fuels and gases is increased by the increase of velocity as well as by the deflection and subsequent decrease of velocity of the gases. The increased relative velocity gives rise to a rapid exchange 15 of material by promoting the removal of the reaction product and the feeding of, and contact between, reactive gas constituents and fuel particles.

The herein described various embodiments of the invention can be carried out alone or in combination with 20 each other, depending upon the most favorable course of the reaction or optimum heat utilization. Decisive for the choice of the specific embodiment to be applied in a given case is the reactivity of the fuel, the melting point of the slag, the dependency of the toughness of the slag 25 on the temperature, and the desired composition of the gas to be produced.

The application of the process according to the invention is not limited to the gasification of fuels. The new process can also be used with advantage for the combustion of fuels wherein the ash is withdrawn in molten form. In the latter case, combustion agents, preferably 30 air, are introduced into the combustion chamber instead of gasifying agents.

It is within the scope of the invention to carry out the 35 process under superatmospheric pressure. The process of the invention and the apparatus adapted to carry out the new process will be more clearly understood when read in conjunction with the accompanying diagrammatic drawings which illustrate some of the various embodiments of the invention by way of example and in which:

Fig. 1 is a side elevation, partially broken away, of a 40 gasifier wherein a slag bath rotates;

Fig. 2 is a sectional view taken on the line 2—2 of the 45 gasifier of Fig. 1.

At the lower section 1 of the body of the gas producer, the gasifying agents and fuels are introduced into the slag bath, tangentially and obliquely toward the bottom of the gasifier, through inlet means 2 and 4 and inlet means 3 and 5 respectively. By the flow energy of the 50

gasifying agents and fuels, the slag bath and all the materials above the slag (gasifying agents, fuel, reaction products thereof and slag droplets) are caused to rotate about the axis of the body at high speed and the solid and liquid portions are thrown onto the wall of the body above the 55 level of the slag bath. The slag and the fuel taken up by the slag flow down the wall back into the slag bath, while the gases and residual fuel stream up in a helical path. Slag runs off through the overflow 6 at the rate slag is newly formed. The gases and fuel ascending 60 in a rotary motion stream through the narrowed portion 7 of the body, their velocity being increased thereby.

The rotary current is deflected by the partition 8 in

the neck 7 into a direction parallel to the axis of the body. Above the neck, the body is widened again. Gas and fuel are distributed all over the sectional area of the portion 9 of the body, their velocity being thereby decreased, and stream up in a uniform path parallel to the axis of the body towards the gas outlet (not shown in the drawing). On this path, the reaction between gas and fuels ceases. The non-gasified residual high-ash fuel can be withdrawn from the gas and returned to the gasification process.

Fig. 3 is a side elevation, partially broken away, of a gasifier wherein the velocity of the gases and the fuels carried along therewith in the body is temporarily increased and the rotary motion of which is deflected into a direction parallel to the axis of the body.

Fig. 4 is a sectional view taken on the line 4—4 of the gasifier of Fig. 3.

The lower portion 10 of the body is constructed as a vortex chamber into which fuels and gasifying agents are introduced tangentially through the pipes 11. The slag formed runs off through the opening 12 at the bottom of the body. The gases and non-gasified fuels moving up in a rotary travel then flow through an annular narrowing 13 of the body and are deflected by the partition walls 14 arranged inside this narrowing into a direction parallel to the axis of the body. The sectional area of the upper portion 15 of the body is widened as desired. Through this section, the gases and fuels stream in uniform distribution at reduced velocity towards the outlet of the body while the gasification reaction ceases.

Fig. 5 is a side elevation, partially broken away, of that portion of a gasifier wherein the stream of the gases and fuels is temporarily increased in velocity and deflected.

Fig. 6 is a sectional view taken on the line 6—6 of the 35 gasifier of Fig. 5.

The lower section 20 communicates with the upper section 21 of the body via openings 22 of partition 22' through which the gases and fuels are passed.

Obviously many modifications and variations of the 40 present invention are possible in the light of the above teachings. It is, therefore, to be understood that within

the scope of the appended claims the invention may be practiced otherwise than as specifically described.

I claim:

A process of gasifying fuels in a circular gasifying apparatus which has separate, distinct and interconnected lower and upper chambers separated by a baffle partition which process comprises introducing the fuel particles and the gasifying agents tangentially into the lower chamber of the gasifying apparatus to cause an upwardly directed whirling and rotating motion of said fuel and agents along the wall of said chamber, the velocity of said fuel particles and gasifying agents remaining substantially uniform during travel through the lower chamber, deflecting the mixture of the produced gas and the incompletely gasified fuel particles rotating along said wall during the gasification from the helical path to a straight line vertical path when the mixture passes from the lower chamber and through the baffle partition, simultaneously increasing the velocity of the mixture as it enters and passes through the baffle partition, maintaining said straight line path as the mixture passes into and through the upper chamber of the gasification apparatus, simultaneously decreasing the velocity of said mixture as it passes into the upper chamber, the incompletely gasified fuel particles of said mixture being distributed during the further gasification uniformly and equally over the entire sectional area of said upper chamber thereby completing the gasification, and withdrawing the produced gas from said upper chamber of the gasification apparatus.
